UNITED STATES PATENT OFFICE.

WILLIAM LEE HANLEY, JR., OF BRADFORD, PENNSYLVANIA.

CAR-PUSHING APPARATUS FOR TUNNEL KILNS.

Application filed April 17, 1923. Serial No. 632,763.

To all whom it may concern:

Be it known that I, WILLIAM L. HANLEY, Jr., a citizen of the United States, residing at Bradford, in the county of McKean and 5 State of Pennsylvania, have invented certain new and useful Improvements in Car-Pushing Apparatus for Tunnel Kilns; and I do hereby declare the following to be a full, clear, and exact description of the invention, such as will enable others skilled 10 in the art to which it appertains to make and use the same.

My invention consists in the novel features hereinafter disclosed, reference being 15 had to the accompanying drawings which show one embodiment of the same selected by me for purposes of illustration, and the said invention is fully disclosed in the following description and claims.

20 My present invention relates to tunnel kilns of the kind in which the goods to be treated are placed on trucks or cars which are moved over rails or tracks extending longitudinally throughout the length of the

25 tunnel kiln, the cars or trucks extending normally from one end of the kiln to the other and the entire train being periodically advanced a car length at a time for the purpose of inserting a fresh car at the forward

30 end of the kiln and discharging the rear car of the train at the rear end of the kiln. In kilns of this character it is usual to move 35 the entire train by force exerted upon the car at the forward end of the kiln, a car pushing mechanism being employed for this purpose.

In the use of a tunnel kiln for the purpose of treating coarse clay products such as brick, tile, etc., it is essential, in order to economically employ the expensive 40 tunnel type of kiln, that the greatest quantity possible of the goods shall be treated continuously and uniformly during the operation of the kiln. These coarse clay products, and especially brick, when loaded upon

45 trucks or cars so as to enable the maximum capacity of the kiln to be utilized for treating or firing the same, necessarily impose an enormous weight upon each car and the force required to propel a train of such

50 heavily loaded cars through the tunnel kiln is necessarily very great. Again, in firing brick and other coarse clay products, they are hacked or piled upon the supporting surfaces of the trucks in a well known manner

55 in superimposed layers so as to form stacks or piles on each car, of considerable height, and it is necessary that the power applied for the purpose of intermittently imparting a forward movement to the train shall be so gradually applied and so gradually released 60 as not to injuriously jar the piles of bricks on the trucks, as otherwise these piles of bricks are liable to be toppled from the cars with the result of producing what is termed a "wreck" within the kiln, by throwing the 65 bricks against the lateral portions of the kiln or between trucks upon the rails. Such a wreck not only results in the destruction of a certain quantity of the goods under treatment, but what is more important it usually 70 necessitates the withdrawal of all the trucks of the train from the kiln and the cooling of the interior of the kiln so as to enable workmen to enter and make the necessary 75 repairs, the cost of such repairs and the further cost of interruption of production being very serious items.

In carrying out my invention I employ a reciprocating pushing member in association with means for imparting to it both a horizontal reciprocating movement longitudinally of the kiln, and a vertical movement into and out of operative relation with a part connected with the car frame it is intended to engage. I also prefer to apply power to this reciprocating member by means of a sprocket chain which is not endless but which engages a driving sprocket to which power is applied from a suitable motor in both directions, and with such speed reduction that the movement of the pushing member into engagement with the last truck of the train, and the application of power to the entire train for propelling it, and also the release of the train from the 80 action of the pushing member, are accomplished so gradually that no appreciable or injurious jarring of the goods carried by the cars results. I also prefer to provide a counter-balance weight for returning the 85 pushing member and sprocket chain to normal position after the train has been advanced the length of a car and means for automatically insuring the vertical movement of the pushing member into and out 90 of operative position.

In the accompanying drawings,

Fig. 1 represents a plan view of my improved pushing mechanism for tunnel kilns, it being shown in connection with a 105

portion of the walls of the kiln, and the truck carrying rails, the walls being indicated in section.

Fig. 2 is a longitudinal section on line 5 2—2 of Fig. 1.

Fig. 3 represents a transverse section.

Fig. 4 is a detail plan view of the reciprocating pushing member, guiding and supporting frame, and showing its connection 10 with the driving sprocket chain and motor balance connection.

Fig. 5 is an elevation of the same, partly in section, illustrating the pushing member in operative position, and in engagement 15 with a part of the car or truck, also showing the means for the automatically vertical movement of the pushing member into and out of operative position.

Referring to the drawings, 1, represents 20 the side walls of a tunnel kiln at the portion thereof near the front or entrance of the kiln. 2, represents a car or truck of any usual or preferred construction, illustrated in dotted lines in Fig. 3, and capable of supporting the weight of the articles to be fired, it being understood that a series of trucks extending the entire length of the kiln are employed in juxtaposition one to another, constituting a train. 3, represents the rails 25 engaged by the truck wheels and extending longitudinally through the kiln. 4, represents my improved longitudinally reciprocating and vertically movable pushing member, which, in the form shown in the drawings, comprises a bar, preferably of wrought metal as iron or steel, and provided at its forward end with an upwardly extending projection or lug, 5, and a bearing portion or heel, 6, on its lower face, said 30 pushing member being provided at its rear end with means for engaging a pivot bolt, indicated at 7. The pushing member, 4, is pivotally connected with a longitudinally movable frame, comprising side bars, 8, 35 connected by a horizontal plate, 9, screwed or bolted thereto, the pivot bolt, 7, extending through the side plates, 8, and the pushing member, 4, and being provided outside of the side plates, 8, with supporting rollers, 10—10, which engage and roll upon horizontal tracks or guides, indicated at 11, extending longitudinally of the kiln and preferably centrally between the rails, 3—3, for a distance somewhat greater than the 40 length of a single car or truck. These guide rails may be formed of angle iron having vertically and horizontally disposed flanges and supported in position by lateral brackets, 12, secured to horizontal supports 45 extending longitudinally of the tunnel, or they may be formed as a trough having upturned lateral edges and secured in the same manner, the supports for the trough being preferably formed of masonry or cement. 50 The forward end of the frame side bars,

8—8, are connected to a massive sprocket chain, indicated at 13, which may rest upon and be supported by the guides, 11, or if preferred the pivots, 14, of the chain may be provided with anti-friction rollers, 15, 70 at opposite sides, as indicated in Fig. 5, although this is not essential. At the extreme forward end of the trough formed by the guides, 11, a recess, indicated at 16, is provided, having a bottom portion, 17, below 75 the lever of the horizontal flanges of the guides, 11, and having an upwardly inclined cam portion, 18, at the rear end of the said recess leading up to the lever of the horizontal flanges of the guides, 11. As will be 80 readily seen, if the reciprocating frame, 8, and sprocket chain is moved rearwardly past the inclined cam, 18, the heel, 6, of the pushing member, 4, will slide down the incline, 18, as indicated in dotted lines in Fig. 2, 85 permitting the pushing member to drop into the position therein shown within the recess, 16, and carrying the lug, 5, out of the path of the lug-engaging portion of the cars so that an additional car can be pushed into 90 the kiln and moved over the top of the pushing mechanism until its lug engaging portion, indicated at 20, in Fig. 5, is forward of the position occupied by the lug when raised to the level of the guides, 11. It will 95 also be seen that the forward movement of the sprocket chain, frame bars 8, and pushing member will cause the heel, 6, to ride up the cam or incline, 18, and elevate the lug, 5, into position to engage the lug-engaging portion, 20, of the car, as clearly indicated in Fig. 5.

Extending transversely of the tracks, 3, at one end of the guides, 11, is located the main driving shaft, 21, of the pushing mechanism. 105 In order to withstand the enormous torsional strain to which this shaft is subjected, it is made of very large diameter and it is connected with the power mechanism by reducing gearing so that it may be rotated at 110 extremely slow speed, practically imperceptible to the eye, in order that no jarring of the piles of bricks or other goods on the cars shall be effected. In the drawings, I have 115 shown a system of gearing which has given excellent results in practice, and I will describe the same, although it will be understood that the particular power mechanism employed and the particular means of transmitting this motion to the driving shaft, 120 may be varied considerably in different installations without departing from my invention. In the present instance, the power which I employ is an electric motor, which, on account of the great speed reduction between it and the driving shaft, 21, may be of 125 comparatively small power, thus effecting a great economy of operation. The motor is indicated at, 22, and is here shown as connected by gears, 23, 24, with a worm shaft, 130

25, provided with a worm (not shown) engaging a worm wheel, 27, on a second worm shaft, 28, on which is located a second worm (not shown), engaging with the worm 5 wheel, 30, of a counter-shaft, 31. This counter-shaft carries a loosely mounted pinion, 32, which engages a large gear, 33, on the driving shaft, 21. A suitable clutch is provided between the pinion, 32, and the 10 shaft, 31. In this instance I have shown a jaw clutch, one member, 34, of which is connected with the loose pinion, 32, and the other member, 35, is splined or keyed on the shaft, 31, and is movable longitudinally into 15 and out of operative position by means of a suitable clutch shifting lever (not shown) which may be of any usual or preferred construction. Any desired speed reduction may be employed in the gearing frame. For example, in the form herein shown, the gear 20 ratios are as follows. The pinion, 23, and gear, 24, constitute a one to three drive. The worm gears constitute approximately one to thirty drives each, and the pinion, 32 and gear, 33, constitute a one to five drive, so 25 that a very great reduction in the speed of the moving parts is effected between the motor, 22, operating at high speed, and the driving shaft, 21. The driving shaft, 21, is provided with a massive sprocket wheel, 35, over which the driving chain, 13, passes, and beneath the sprocket wheel, 35, is a pit or receptacle, indicated at 36, into which the free 30 end of the sprocket chain, indicated at 13^a, 35 may descend when the pushing apparatus is operated in the direction to push the train of trucks or cars forward through the tunnel. I also prefer to employ a reversible motor 40 operated in any usual or well known manner, although it will be understood that I may use a non-reversible motor, and provide suitable gearing for reversing the direction of the driven parts, if desired. I prefer, however, to employ the reversible motor and 45 eliminate reversing gearing.

I also prefer to provide means for retracting the pushing member and sprocket chain after the train of cars has been moved forward the required distance, so as to leave the 50 pushing apparatus in position to receive another car at the forward or front end of the kiln. In the present instance, I have shown a counter-weight, 37, movable vertically in a pit, 38, and connected by means of a cable, 39, passing over a sheave, 40, with a plate, 19, secured to the reciprocating frame bars, 8, carrying the pushing member, 4. Suitable means are preferably provided for limiting the rearward movement of the pushing member and chain. For example, I may provide a cushion block, indicated at 41, located at the bottom of the pit to arrest the downward movement of the weight, 37. The return movement of the sprocket chain and pushing member will be resisted by the friction

of the drive shaft, 21, and the intermeshing pinion and gear, 32-33, the clutch 34-35, being at the time disengaged, so that the weight, 37, will restore the sprocket chain and pushing member to the position indicated in Fig. 2, without jar. 70

The operation of my improved car pushing apparatus is as follows. Assuming the parts to be in the position indicated in Fig. 2, in which the pushing member, 4, is in 75 its depressed and inoperative position to which it has been retracted by the weight, 37, a car is moved by hand, or otherwise, until the portion, 20, thereof, which is to be engaged by the pushing member, is 80 slightly forward of the position occupied by the lug, 5, of the pushing member. The clutch, 34-35, is engaged and the motor, 22, is started, thereby imparting a very slow forward movement through the intermediate gearing before described, to the driving shaft, 21, sprocket, 35, and sprocket chain, 13. As the chain moves forward the heel of the pushing member slides up the incline, 18, see Fig. 5, into operative position in rear of the portion, 20, of the truck, which it is intended to engage and the continued operation of the motor and forward movement of the sprocket chain applies the power of the motor very efficiently and very 85 gradually to the freshly added car of the train and gradually takes up the load of the entire train until all the cars of the train are moving forwardly toward the delivery end of the kiln, the motion being so gradual that there is no bumping of backlash or jolting of the cars, and no danger of toppling the piles of bricks or other goods carried thereby. This movement proceeds until 90 the entire train has been moved forward a distance substantially equal to the length of one of the cars or trucks. It will be understood that if the pressure exerted by the pushing member were relieved there would be a certain amount of backlash in 95 the train which would have a tendency to disturb the balance of bricks or other goods carried thereby, with disastrous results. I therefore, at this point in the operation of the device, reverse the movement of the driving shaft, 21, in this instance by reversing the motor and the movement in the reverse direction takes place at the same slow speed under the action of the reducing 100 gearing, as the forward movement, thereby 105 relieving the great pressure exerted on the last truck by the pushing member so gradually and slowly that there is no backlash and no jostling of the loaded cars. As soon as the pushing member has been withdrawn far enough to be out of contact with the member, 20, of the last truck which it 110 engages, the motor is stopped and the clutch members, 34-35, are separated by operating a suitable shifting lever (not shown). 115 120 125 130

Thereupon the counter-balance weight, 37, which has been raised by the forward movement of the sprocket chain and pushing member, settles to the bottom of its pit, 38, and draws back the pushing member and sprocket chain to their normal positions, indicated in Fig. 2, the weight coming to rest on the cushion, 41. This movement under the action of the counter-balance weight will of course be much more rapid than the operation under the action of the motor, but will be retarded by the friction of the driving shaft and gears, 32 and 33, as before described, so that the parts will come to rest without shock. The counter-balance weight enables me to restore the parts to normal position in a very simple and expeditious manner, without the necessity of providing special gearing, and also effects an economy of power, as the motor is thrown out of operation as soon as the pushing member has been disengaged from the last car.

It will be understood that in place of the electric motor, 22, I may employ any other form of prime motor, or I may drive from line shafting or in any other desired way. The various parts of the apparatus are made in such a manner as to provide the greatest possible strength and the bearings for the various moving parts are supported upon heavy masonry or cement bases or upon heavy metal beams, so as to provide a rigid and durable construction. By employing a sprocket chain which is not endless and which is given a reciprocating movement instead of a continuous movement in the same direction, I am able to obtain all the advantages of the sprocket chain drive for the pushing member without any change in the relation between the pushing member itself and the part on the rearmost car or truck which it engages, and I am also enabled to back off the pushing member very slowly and gradually so as to relieve the enormous pressure necessarily exerted on the rear car for the purpose of moving the entire train forward, without any shock to the cars of the train and without any danger of backlash or breakage of the driving mechanism.

What I claim and desire to secure by Letters Patent is:—

1. In a car pushing apparatus for tunnel kilns, the combination of a horizontally disposed sprocket chain, means for moving said chain longitudinally in both directions, a pushing member having a pivotal connection with said chain, and having a car engaging part movable vertically into and out of operative relation with a car to be pushed, and means for engaging the movable pushing member for elevating said car engaging part into and holding it in operative position.

2. In a car pushing apparatus for tunnel kilns, the combination of a horizontally disposed sprocket chain, means for moving said chain longitudinally in both directions, a horizontally disposed guide for supporting said chain, a pushing member pivotally connected with a portion of said chain supported by said guide, and provided with a car engaging portion movable vertically into and out of operative relation with a car to be pushed, and a cam for engaging the vertically movable portion of said pushing member for elevating it into operative position, said guide being provided with means for holding said pushing member in operative position during a portion of its longitudinal movement with said chain.

3. In a car pushing apparatus for tunnel kilns, the combination of a horizontally disposed sprocket chain, a pushing member pivotally connected therewith and having a car engaging part movable vertically into and out of operative relation with a car to be pushed, means for applying power to said chain to move it and said pushing member forwardly, a counter balance for moving said chain and pushing member back to normal position, a cam for raising the vertically movable portion of said pushing member into operative position, and supporting means for supporting said chain in horizontal position and supporting said pushing member in operative position.

4. In a car pushing apparatus for tunnel kilns, the combination of a pushing member, a horizontal reciprocating sprocket chain connected therewith, a power operated driving sprocket engaging said chain, and means for operating said driving sprocket in both directions.

5. In a car pushing apparatus for tunnel kilns, the combination of a pushing member, a horizontal reciprocating sprocket chain connected therewith, a power operated driving sprocket engaging said chain, means for operating said driving sprocket in both directions, means for disconnecting the driving sprocket from the power operating mechanism, and independent means for restoring the pushing member and sprocket chain to normal position.

6. In a car pushing apparatus for tunnel kilns, the combination of a pushing member, a horizontal reciprocating sprocket chain connected therewith, a driving sprocket engaging said chain, power operated means for rotating said sprocket in both directions, clutch mechanism interposed between the driving sprocket and said power operated mechanism, and a counter-balance operatively connected with said pushing member and sprocket chain for restoring them to normal position.

7. In a car pushing apparatus for tunnel kilns, the combination of a pushing member, a horizontal reciprocating sprocket chain connected therewith, a driving sprocket engaging said chain, power operated mechanism including reducing gearing connected with said driving sprocket and operable for driving said sprocket in both directions, a clutch for disconnecting the power operated mechanism from the driving sprocket, and a counter-balance connected with said pushing member and sprocket chain for restoring them to normal position.
- 10 8. In a car pushing apparatus for tunnel kilns, the combination of a pushing member, reciprocable horizontally, power operated means including reducing gearing for imparting slow movement to said pushing member in both directions, and independent means for moving said pushing member in a direction to retract the same to normal position.
- 15 9. In a car pushing apparatus for tunnel kilns, the combination of a pushing member, power actuated mechanism including reducing gearing for imparting slow movement to said pushing member in both directions, means for disconnecting said power operated mechanism from the pushing member, and a counterbalance weight connected with said pushing member for retracting the same to normal position after operation.
- 20 10. In a car pushing apparatus for tunnel kilns, the combination of a reciprocating frame, a pushing member pivotally mounted in said frame and having a part capable of vertical movement with respect to the frame, a sprocket chain connected with the frame, a horizontal track for supporting said frame, a power operated driving sprocket engaging said chain, reciprocating means for said frame, and a cam located in the path of said pivoted pushing member for elevating it into operative position.
- 25 11. In a car pushing apparatus for tunnel kilns, the combination of a horizontal supporting track, a reciprocating frame supported thereon, a reciprocating sprocket chain connected with said frame and supported by said track, a pushing member carried by said frame, a driving sprocket engaging said sprocket chain, a counter-balance weight and a flexible connection between the counter-balance weight and said frame.
- 30 12. In a car pushing apparatus for tunnel kilns, the combination of a pushing member movable vertically into and out of oper-
- ative position, a horizontally movable sprocket chain operatively connected with said pushing member, for moving the same horizontally, a driving sprocket engaging said chain, a prime motor, reducing gearing interposed between the prime motor and said sprocket for driving the same in both directions, a clutch interposed between said driving sprocket and the motor, and means independent of the motor for moving said pushing member and sprocket chain horizontally in a direction to restore them to normal position.
- 35 13. In a car pushing apparatus for tunnel kilns, the combination of a horizontal reciprocating frame, a supporting track for the same, a pushing member pivoted in said frame and capable of vertical movement into and out of operative position, a reciprocating sprocket chain connected with said frame, a driving sprocket engaging said chain, driving mechanism including reducing gearing for driving said sprocket in both directions, a clutch interposed between said sprocket and said driving mechanism, a counter-balance weight, a flexible connection from said weight to said frame, and a cam located in the path of said pivoted pushing member for elevating the same into operative position.
- 40 14. In a car pushing apparatus for tunnel kilns, the combination of a horizontally disposed non-endless sprocket chain, a horizontal supporting guide therefor, a power operated sprocket engaging said chain, a counter balance operatively connected to said chain, a pushing member pivotally connected to said chain and having a vertically movable car engaging portion, a stationary cam for engaging said pushing member for raising the car engaging portion thereof into operative relation with a car to be pushed, and means for holding said pushing member in operative position during the reciprocating movements of said chain.
- 45 15. In a car pushing apparatus for tunnel kilns, the combination of a horizontally disposed, reciprocable, non-endless sprocket chain a power operated sprocket engaging said chain adjacent to one end a counter balance connected to said chain adjacent to its other end a pushing member connected to said chain and provided with a vertically movable car engaging portion, and means for raising said car engaging portion of the pushing member into and holding it in operative relation with a car to be pushed.

In testimony whereof I affix my signature.

WILLIAM LEE HANLEY, JR.
